[57] CLAIM

The ornamental design for a ring, substantially as shown and described.

DESCRIPTION

FIG. 1 is a top plan view of a ring showing my new design;
FIG. 2 is a front elevational view thereof;
FIG. 3 is a bottom plan view thereof;
FIG. 4 is a side elevational view thereof;
FIG. 5 is an elevational view of the side opposite that shown in FIG. 4;
FIG. 6 is a top plan view of a ring showing a modified form of my new design; and
FIG. 7 is a front elevational view thereof.
